UNITED STATES PATENT OFFICE.

LEWIS FERRY MOODY, OF PHILADELPHIA, PENNSYLVANIA.

IMPULSE TURBINE.

Original application filed May 26, 1923, Serial No. 641,638. Divided and this application filed September 21, 1925. Serial No. 57,492.

This invention relates to impulse turbines and particularly to impulse turbines having a jet of cylindrical form directed against buckets carried at the periphery of the runner. The object of the invention is to provide such a turbine having the jet or jets directed into the peripheral portions of the buckets and turned by the buckets and discharged on one side of the rotor.

Further objects of the invention particularly in turning and spreading the flow in gradual and efficient manner will appear from the following description taken in connection with the accompanying drawings in which

Fig. 1 is a vertical sectional view through a runner of a turbine embodying the invention.

Fig. 2 is a horizontal sectional view on line 2—2 of Fig. 1.

Fig. 3 is a sectional development of buckets of the Fig. 1 runner taken on the cylindrical surface indicated at 3—3 in Figs. 1 and 2.

Fig. 4 is a vertical sectional view of a modified form of runner.

Fig. 5 is a plan view of the same, and

Figs. 6, 7 and 8 are sectional views of the runner buckets taken on cylindrical surfaces 6—6 and 7—7 and conical surface 8—8 respectively of Figs. 4 and 5.

In the specific embodiment of the invention shown in Figs. 1 to 3 a vertical shaft 10 carries at its lower end the runner 11 having hub portion 12 carrying the peripheral buckets 13 sixteen in number. The surface 14 of the hub 12 at the buckets is concave in section curving smoothly from a radial direction at the entrance edges 15 of the buckets toward an axial direction at the discharge edges 16.

From this surface the buckets 13 extend downward and outward in shallow curved form adapted to receive and turn and spread the cylindrical jet from nozzle 17 as indicated by broken lines on the drawings. The horizontal elements of each bucket face 20 taken in horizontal planes are relatively flat concave curves (Fig. 2) from the bucket tips 18 to the line 19 of junction with the hub surface 14 while the vertical elements taken in vertical cylinders coaxial with the runner are more deeply concave (Fig. 3) curving forward and then backward to the discharge edge 16. The faces 20 of the buckets as cut by a horizontal plane (Fig. 2) incline backward and outward to form an angle β_1 in their

entrance portions with relation to tangents to the circle of revolution at the blade tips of the runner, to co-operate properly with the jet which is directed horizontally against the buckets with both tangential and inward components, forming an angle α_1 with the tangential direction. The angle α_1 is specifically shown as being less than 45° , the jet being in a more approximately tangential direction.

The water in passing through each runner bucket 13 is simultaneously spread and turned into a backward direction making a small angle β_2 with the tangential direction, so that its relative velocity is nearly equal and opposite to the motion of the bucket at the point of discharge; and the water is discharged from each bucket as a thin sheet and with but little absolute velocity remaining in it. The inner lines of flow 22, as to their meridian components, are curved gradually from a radial inward direction into a nearly axial direction and the outer lines 23 are curved around from radial inward to a downward and outward direction. Between these extremes the jet is spread out gradually in thin sheet form discharging downward in a generally axial direction.

In the runner of Figs. 1 to 3 the flow is turned from radial toward axial entirely by the bucket surfaces without contact with the surface 14 of the runner crown or hub 12. The extended line of connection between each bucket and the crown 12 provides a strong support for the buckets and usually a shroud ring will be unnecessary, leaving the exposed edges of the buckets free and giving easy access to the bucket surfaces for grinding and finishing.

In the modification shown in Figs. 5 to 8 the runner hub or crown 32 has its concave peripheral surface 34 provided with the buckets 33 having concave faces 30 receiving the jet from nozzle 37 at the entrance edge 35 and turning and spreading and decelerating the flow to finally discharge it at 36 as a thin sheet between the inner lines 42 and the outer lines 43. The entrance edges 35 are contained in a vertical cylindrical surface and the lower portions of the buckets are extended laterally to provide for a wide lateral spreading of the jet as it passes through the bucket.

The faces 30 of the buckets merge smoothly with the surface 34 of the runner crown and part of the guidance of the water is provided

by this surface 34. The shape of the bucket is shown in Figs. 6, 7 and 8 in developed sections cut by cylindrical or conical surfaces. The jet flow is received with inward and tangential components and while it is being spread and turned backward it is guided downward and outward to a generally axial discharge. The buckets 33 instead of inclining outwardly and forwardly at their entrance portions 35 are nearly radial at these portions as viewed in horizontal section or inclining slightly backward and outward. Progressing inwardly toward the hub these buckets curve inward and backward on smooth lines which reach a substantially tangential direction at the line of mergence with the crown surface 34.

In both the runners shown successive buckets overlap in axial projection as indicated in Figs. 2, 3, 5, 6 and 7 so that the discharge edge of one bucket lies under the upper entrance portion of the following bucket. While only one nozzle is shown in the drawings it is obvious that a plurality of nozzles may be used and the turbine installed in any desired setting adapted for instance to maintain a partial vacuum in the runner chamber. The jets may be directed at any desired angle so as to vary the relative inward and tangential components to suit different conditions and without departing from the principle of the invention various modifications may be resorted to within the scope of the appended claims.

35 In particular, when a very high specific speed is desired the angle α_1 can be made greater than 45° and the buckets inclined forward with a considerable angle β_1 . In securing a high specific speed, it will be advantageous in many cases to combine the forward inclination of the buckets of Fig. 2 with the lateral extension of the discharge edges of the buckets shown in Fig. 4. This may be done either by modifying the runner of Figs. 1 and 2 to extend the outflow edges of the blade outwardly from the axis to a greater diameter than the inflow edges or by modifying the runner of Figs. 4 and 5 so as to give the entrance edges of the vane a forward angle of inclination with respect to the radius similar to that shown in Fig. 2. When the laterally extended buckets are used, this outward extension may for high specific speeds be carried to the extent where the buckets will extend under and beyond the nozzle, the entrance portion of the bucket being cut away sufficiently to clear the nozzle. It is desirable to have the nozzle orifice as close as possible to the entrance edges of the buckets in order to minimize the length of free path traversed by the jet between the orifice and the bucket edges. The nozzles indicated in the figures are of the type in which the size of the jet is controlled by a central needle. The needle may be of rela-

tively short form having the sides of its tip converge at a considerable angle at the point, thus permitting the nozzle to be placed close to the vane edges.

(This application is a division of my application, No. 641,688, filed May 26, 1923, now Patent No. 1,554,574.)

I claim:

1. In an impulse turbine means for forming a cylindrical free jet having its axis substantially in a plane perpendicular to the runner axis, and a runner having buckets receiving said jet and turning all of it toward the axial direction and discharging it on one side of the runner, the flow between adjacent buckets having a free surface, said jet being more tangential than radial with respect to said runner. 75

2. In an impulse turbine means for forming a cylindrical free jet having its axis substantially in a plane perpendicular to the runner axis, and a runner having buckets receiving said jet and turning all of it toward the axial direction and spreading it laterally so that the inner lines of the discharge have inward components and the outer flow lines have outward components, said jet being more tangential than radial with relation to said runner and the flow between adjacent buckets having a free surface. 85

3. In an impulse turbine means for forming a cylindrical free jet having its axis substantially in a plane perpendicular to the runner axis, and a runner having buckets receiving said jet and turning all of it toward the axial direction and discharging it on one side of the runner, said jet having both tangential and radial components at the point of entrance to said buckets, said jet being more tangential than radial with relation to said runner and the flow between adjacent buckets having a free surface. 95

4. In an impulse turbine means for forming a cylindrical free jet having its axis substantially in a plane perpendicular to the runner axis, and a runner having buckets receiving said jet with a free surface for the flow between adjacent buckets and turning all of it toward the axial direction and spreading it laterally so that the inner lines of the discharge have inward components and the outer flow lines have outward components, said jet having both tangential and radial components at the point of entrance to said buckets and the tangential component being greater than the radial component. 110

5. In an impulse turbine means for forming a cylindrical free jet having its axis substantially in a plane perpendicular to the runner axis, and a runner having buckets with faces directed substantially radially at their entrance portions and turning all of said jet to one side of said plane, the flow between adjacent buckets having a free surface. 125

6. In an impulse turbine means for form-

ing a cylindrical free jet having its axis substantially in a plane perpendicular to the runner axis, and a runner having buckets with faces directed substantially radially at 5 their entrance portions and turning all of said jet to one side of said plane, said jet at the point of entrance to the buckets having both radial and tangential components and the flow between adjacent buckets having a 10 free surface.

7. In an impulse turbine means for forming a cylindrical free jet having its axis substantially in a plane perpendicular to the runner axis, and a runner having buckets 15 with faces inclined forward and outward at their inner portions and being substantially radial at their outer entrance portions and turning all of said jet to one side of said plane and discharging it in a generally axial direction, 20 said jet at the point of entrance to the buckets being substantially tangential, and the flow between adjacent buckets having a free surface.

8. In an impulse turbine, in combination, 25 means for forming a cylindrical free jet comprising a nozzle with a central adjustable needle and directing said jet in a plane perpendicular to the runner axis and a runner having buckets with the entrance portion of 30 their faces inclined at a forward angle with respect to the radial direction at their inner portions and being substantially radial at their outer entrance portions and discharging all of said jet on one side of the runner, 35 the flow between adjacent buckets having a free surface.

9. In an impulse turbine, in combination, 40 means for forming a cylindrical free jet comprising a nozzle with a central adjustable needle and directing said jet in a plane perpendicular to the runner axis in a more tangential direction than radial, and a runner receiving said jet and discharging all of said 45 jet on one side of the runner, and the flow between adjacent buckets having a free surface.

10. In an impulse turbine means for forming a cylindrical free jet having its axis substantially in a plane perpendicular to the runner axis and a runner having buckets receiving said jet and discharging all of it on 50 one side of the runner, said jet having a greater tangential than radial component at the point of entrance to said buckets, and the flow between adjacent buckets having a free 55 surface.

11. In an impulse turbine means for forming a cylindrical free jet having its axis substantially in a plane perpendicular to the runner axis, and a runner having buckets receiving said jet and spreading it laterally so 60 that a portion of said jet is directed in the axial direction at discharge and a portion is directed outwardly from the axis, said jet having a greater tangential than radial component at the point of entrance to said 65

buckets, and the flow between adjacent buckets having a free surface.

12. In an impulse turbine means for forming a cylindrical free jet having its axis substantially in a plane perpendicular to the runner axis but having a direction more nearly tangential than radial in said plane, and a runner having buckets with the inner portion of their faces inclined forward of the radial direction and with the outer entrance portion 70 of their faces substantially radial and turning all of said jet to one side of said plane, the flow between adjacent buckets having a 75 free surface.

13. In an impulse turbine the combination 80 with a rotor having a vertical axis and buckets with substantially radially directed surfaces and adapted to turn the entire flow from horizontal downward to one side of said rotor, of a nozzle forming a horizontal cylindrical jet and directing it substantially tangentially against the substantially radially directed surfaces of said buckets so that the turbine will have a moderate specific speed.

14. In an impulse turbine means for forming a cylindrical free jet having its axis substantially in a plane perpendicular to the runner axis, and a runner having buckets receiving said jet and turning all of it toward the axial direction and discharging it 90 on one side of the runner, the flow between adjacent buckets having a free surface, the axis of said jet subtending a small angle to the tangential direction at the entrance edge 95 of said buckets.

15. In an impulse turbine an adjustable needle nozzle for forming a cylindrical free jet having its axis substantially in a plane perpendicular to the runner axis, and a runner having buckets receiving said jet with a 100 free surface for the flow between adjacent buckets and turning all of it toward the axial direction and spreading it laterally so that the inner lines of the discharge have inward components and the outer flow lines 105 have outward components, said jet having both tangential and radial components at the point of entrance to said buckets and the tangential component being greater than the radial component.

16. In an impulse turbine means for forming a cylindrical free jet having its axis substantially in a plane perpendicular to the runner axis but having a direction more nearly tangential than radial in said plane, 110 and a runner having buckets with the inner portion of their faces inclined forward of the radial direction and with the outer entrance portion of their faces inclined at only a small angle to the radial direction and turning all of said jet to one side of said plane, the flow between adjacent buckets having a 115 free surface.

17. In an impulse turbine the combination 120 with a rotor having a vertical axis and

- buckets having the outer entrance portion of their faces inclined backwardly of the radial direction at a small angle to the radius at their entrance edges and adapted to turn the entire flow from horizontal downward to one side of said rotor, of a nozzle forming a horizontal cylindrical jet and directing it with a tangential component against the substantially radially directed surfaces of said buckets so that the turbine will have a moderate specific speed.
18. The combination set forth in claim 1 having the buckets provided with a discharge edge which has at least a portion curved in plan view.
19. The combination as set forth in claim 1 having the buckets provided with a discharge edge which in plan view has its outer portion curved forwardly while its inner portion is substantially straight and radially disposed.
20. The combination as set forth in claim 1 having the buckets shaped so that in a circular section parallel to the runner axis the bucket is disposed substantially entirely backward of the entrance portion.
21. The combination as set forth in claim 5 further characterized by having the buckets provided with a discharge edge which has at least a portion curved in plan view.
22. The combination as set forth in claim 5 further characterized by having the buckets provided with a discharge edge which, in plan view, has its outer portion curved forwardly, while its inner portion is substantially straight and radially disposed.
23. The combination as set forth in claim 5 further characterized by having the buckets shaped so that in a circular section parallel to the runner axis the bucket is disposed substantially entirely backward of the entrance portion.
24. The combination as set forth in claim 8 further characterized by having the buckets provided with a discharge edge which has at least a portion curved in plan view.
25. The combination as set forth in claim 1 further characterized in that said buckets have a greater radial than axial extent.
26. The combination as set forth in claim 12 further characterized in that said buckets have a greater radial than axial extent.
27. The combination as set forth in claim 12 further characterized in that said buckets have a greater radial than axial extent and have an entrance edge which in elevation is disposed radially inwardly of the outermost portion of the buckets.
28. The combination as set forth in claim 1 further characterized by having a jet which is variable while still preserving its cylindrical form and having buckets overlapping each other in axial projection.
29. The combination as set forth in claim 12 further characterized by having a jet which is variable while still preserving its cylindrical form and having buckets overlapping each other in axial projection.
30. The combination as set forth in claim 12 further characterized in that said buckets overlap each other in axial projection and have a greater radial than axial extent while the size of the cylindrical jet is adapted to be varied while still preserving its cylindrical form.

LEWIS FERRY MOODY.
